ALPHABET FOR MONOGRAMS OR THE LIKE

George Berlant, Bellerose, N.Y., assignor to New Hermes
Engraving Corporation, New York, N.Y.

Original design application Nov. 12, 1969, Ser. No.
20,033. Divided and this application Feb. 8, 1971, Ser.
No. 113,815

Term of patent 14 years

Int. Cl. D18—03
U.S. Cl. D64—16

FIG. 1

FIG. 2

FIG. 1 is a face view of an alphabet for monograms showing my new design; and

FIG. 2 is a face view of another embodiment thereof wherein double rather than triple lines are employed.

This is a division of design application Ser. No. 20,033, filed Nov. 12, 1969.

I claim:

The ornamental design for alphabet for monograms or the like, substantially as shown and described.
